US00D327116S

United States Patent [19]

Prina

[11] Patent Number: Des. 327,116

[45] Date of Patent: ** Jun. 16, 1992

[54] ELECTROPNEUMATIC PRESSURE
REGULATOR WITH INTEGRATED
ELECTRONIC CONTROL

[75] Inventor: Raphaël Prina, Perly, Switzerland

[73] Assignee: Honeywell Lucifer S.A., Carouge,
Switzerland

[**] Term: 14 Years

[21] Appl. No.: 343,944

[22] Filed: Apr. 25, 1989

[30] Foreign Application Priority Data

Nov. 3, 1988 [XH] Hague DM/012108

[52] U.S. Cl. D23/235

[58] Field of Search D23/233-237,
D23/243-249; 137/116.5, 505.14, 625.65

CLAIM

The ornamental design for an electropneumatic pressure regulator with integrated electronic control, as shown.

DESCRIPTION

FIG. 1 is a right side elevational view of an electropneumatic pressure regulator with integrated electronic control; showing my new design;

FIG. 2 is a front elevational view thereof;

FIG. 3 is a left side elevational view thereof;

FIG. 4 is a rear elevational view thereof;

FIG. 5 is a top plan view thereof; and,

FIG. 6 is a bottom plan view thereof.

FIG. 1

FIG. 2

FIG. 3

FIG. 4

FIG. 5
